UNITED STATES PATENT OFFICE.

JOSEPH W. ROWELL, OF SAN FRANCISCO, CALIFORNIA.

TERRA-COTTA AND OTHER FIREPROOF CONSTRUCTIONS.

SPECIFICATION forming part of Letters Patent No. 531,134, dated December 18, 1894.

Application filed July 29, 1893. Serial No. 481,864. (No model.)

To all whom it may concern:

Be it known that I, JOSEPH W. ROWELL, a citizen of the United States, and a resident of the city and county of San Francisco, State 5 of California, have invented certain new and useful Improvements in Terra-Cotta and other Fireproof Constructions; and I do declare the following to be a full, clear, and exact description of the invention, such as will enable others skilled in the art to which it appertains to 10 make and use the same.

My invention relates to the building of arches, partitions, and other structures of the same type made of terra cotta or similar hollow tiles.

The object of said invention is to provide an improved mode of construction whereby persons of ordinary skill will be enabled to put up structures of the class referred to with 20 ease and dispatch and without the aid of props or supports as now used, yet making shapely structures of unusual strength and so well joined, united and bound up as to be practically immovable, impenetrable to fire, 25 and proof against earthquakes.

Referring to the accompanying drawings, in two sheets, for a detailed description of my invention,—Figure I is a sectional elevation of a floor arch containing my improvements. Fig. II is a top view of the same, the floor and a temporary clip used in putting up the arch being removed. Fig. III is a detailed view, in perspective, of an improved tile forming part of my construction. Fig. 30 III^A is a broken sectional elevation of an arch of modified form. Fig. IV is a side elevation of a tile partition also embodying my invention. Fig. V is a vertical cross-section taken from Fig. IV. Fig. VI is a plan of the structure shown in the two preceding figures. Fig. VII is an elevation showing my improved 35 method of arching over openings in partitions. Fig. VIII is a perspective view of the form of tile which I consider most suitable for partitions.

Corresponding parts are designated by corresponding letters of reference in all the views.

Let A B C represent hollow tiles, such as 40 are used in the construction of floors of various edifices, and which may be of any de-

sirable shape, size, and material, though now made of terra cotta. In the sides of each tile I form a rabbet *x* by means of which the tiles are made to lap over one another and which 55 is so designed as to form a radiating joint, as shown in the drawings. For arches of the nature represented in Fig. I the tiles are rabbeted on a plane coinciding with that of the upper surface of the arched strengthening 60 rib *y* in order that each may be readily picked out and set in its proper place in the structure of which it is to form a part.

Besides the rabbet *x* I provide each tile with a lip or rim *a* projecting outwardly from 65 one end and adapted to be inserted and fitted into the opposite end of the preceding tile, thus affording a tailed butt joint in lieu of the straight butt-joint heretofore in vogue. This lip or rim may be either continuous or broken 70 in places, as illustrated in Figs. III and VIII.

b indicates a lip, ledge or flange which may be substituted for the rabbet *x* in the sides of the tile, projecting from one of the upper edges or corners of the tile as shown. 75

Fig. III^A represents one half section through an arch whose voussoirs are formed with straight radiating joints at the top of which such a lip, ledge or flange laps over onto the top of the adjoining voussoir. This form of 80 hollow tile voussoirs may be used with the tailed butt joint as in the case of the rabbeted voussoirs shown in Fig. I and will accomplish the same result.

The rabbet and corner flange are replaced 85 in partition tiles by an angular projection *c* at one side and a corresponding angular depression or groove *d* in the opposite side of each tile as indicated in Fig. VIII. These form vertical dovetail joints and strengthening divisions and give lateral strength to the partition.

Each tile, whether made for partition or arch work, is also provided with a repetition or series of dovetail depressions *e* in one or 90 both of its surfaces as may be required. This peculiarity of conformation affords a key for the plastering and therefore tends to consolidate the whole work when completed.

D D' represent skewback tiles used in the 100 construction of arches. These I form with a continuous upwardly-projecting beveled

flange *f* by means of which the skewback tiles may be held in position by temporary metal clips *E*, Fig. I, until the key-tile has been set in position. Another improvement 5 in the construction of these tiles consists in beveling the inner side of their lower members *h* which cover and protect the lower flange of the steel beams *F*, thereby forming an air space between the tiles and the bottom 10 of the beams.

It will be observed that by using my improved tiles an arch can be set in position without the use of centering or scaffolding along its under surface, and without the use 15 of iron or steel bearers in the construction of the arch, as, after the tiles marked A in Fig. II have been set, the rest of the tiles composing the arch may be slipped in alternately between the projecting members of the course 20 last set.

The rabbeted radiating joint insures the stability of the separate members while the process of setting them without centering or other support from below is carried out and 25 operates to vastly increase the stability and rigidity of the entire arch after it is finished. The rabbet in the radiating joint coinciding with the upper line of the arched strengthening rib obviates the possibility of a mistake 30 in setting the arch, since, the rabbet being necessarily at a different position in each different radiating joint, no tile except the one intended for the place can be used. This is an improvement on all straight radiating 35 joint arches as even skilled workmen in setting the latter often make mistakes in selecting the proper tile for the position, endangering the safety of the arch. The rabbet furthermore prevents any deflection or sagging 40 of the lower surface of the arch. A further improvement is to be found in the peculiar adjustment of the arched strengthening rib with rabbet in joint which gives the best possible arrangement for strength. The principle 45 of the rabbeted radiating joint is further susceptible of practical application in the building of arches over openings in hollow

tile partitions, as indicated in Fig. VII. There the rabbeted radiating joint makes the superincumbent weight dependent on an arch 50 for support instead of bearing on the door head or being sustained by the cohesion of the mortar in the joints. The same results, it will be noticed, are obtained by following the construction illustrated at Fig. III^A. 55

Having the butt joints tailed, as set forth, and especially using the same in connection with the rabbeted radiating joints tends to further consolidate a structure made of hollow tiles, whether arch, partition, or similar work. In an arch, for instance, the tailed butt joints render each longitudinal row of tiles practically a continuous voussoir while the rabbeted joint secures each voussoir from an upward or downward movement. This 60 makes the completed arch immovable and absolutely earthquake proof, as the voussoirs cannot be dislodged by either an upward, downward or lateral thrust. In a partition, the projecting rim or lip on the lower edge of 65 the tile fitting down into the opening in the upper end of the preceding tile, as illustrated in Fig. V, obviates the necessity of metal clamps in setting, thereby making the partition wholly of fire-proof material, and together with the dovetail or angular joints 70 precludes the possibility of its being swayed from side to side.

Having now described my invention, what I claim as new, and desire to secure by Letters 80 Patent of the United States, is—

A hollow tile having an arched strengthening rib and having longitudinal rabbets on its sides in a plane coinciding with that of the upper surface of the strengthening rib, 85 and provided at one end with a projecting lip or rim.

In testimony whereof I affix my signature in presence of two witnesses.
